UNITED STATES PATENT OFFICE.

JOHN A. SUTPHEN, OF ZANESVILLE, OHIO.

DESIGN FOR A GUITAR.

SPECIFICATION forming part of Design No. 23,725, dated October 23, 1894.

Application filed July 21, 1894. Serial No. 518,279. Term of patent 3½ years.

To all whom it may concern:

Be it known that I, JOHN A. SUTPHEN, a citizen of the United States, residing at Zanesville, in the county of Muskingum and State of Ohio, have invented and produced a new and original Design for Guitars, of which the following is a specification.

The drawing fully illustrates my design.

My design relates to musical instruments and particularly to that class known as guitars, and it consists in a guitar body, crescent-shaped in outline, provided with a neck and having a star-shaped opening and crescent-shaped bridge, all as shown in the drawing.

A, represents the body of the guitar having 15 the vertical curved wall b.

C represents the neck; D, the star-shaped opening; E, the crescent-shaped bridge, as illustrated.

Having thus described my design, what I 20 claim is—

The design for a guitar, as herein shown and described.

JNO. A. SUTPHEN.
